UNITED STATES PATENT OFFICE.

LOUIS H. BRINKMAN, OF GLEN RIDGE, NEW JERSEY, ASSIGNOR TO BALL ROLLED TUBE CORPORATION, A CORPORATION OF NEW YORK.

APPARATUS FOR DRAWING METAL.

1,203,306.

Specification of Letters Patent. Patented Oct. 31, 1916.

Application filed October 16, 1914. Serial No. 868,926.

To all whom it may concern:

Be it known that I, LOUIS H. BRINKMAN, a citizen of the United States, and a resident of Glen Ridge, county of Essex, State of New Jersey, have invented certain new and useful Improvements in Apparatus for Drawing Metal, of which the following is a specification.

My invention relates to apparatus for drawing metal.

One of the objects of the invention is to provide a durable and efficient die for this purpose.

The invention in its preferred embodiment is especially useful for drawing hot metal, and more particularly for drawing hot tubes, although it will be obvious to those skilled in the art, after understanding my invention, that certain of its features are useful in drawing cold rods or tubes.

Another object of the invention is to provide for cooling the die parts when drawing hot metal, by using fluid forced through the die parts by or by the aid of centrifugal force, and in the preferred embodiment of my invention using die balls, to cool the die balls by direct contact of the fluid and wash out the scale from the raceway in such manner that the fluid is conveyed off without coming in contact with the hot metal to chill it and thus interfere with the drawing operation.

Another object of the invention is the provision of rotary die apparatus having a plurality of sets of die balls which, in the preferred embodiment of the invention, are so arranged that each set may be separately adjusted radially to vary the diameter of the die thereat.

When the apparatus is constructed for drawing tubes, I may provide a mandrel cooperating with the two sets of die balls, in such manner that one set of balls acts to reduce the thickness of the metal while the other set acts to reduce the inner diameter of the tube, although where such operation is not desired, both sets of balls may act simply to reduce the thickness of the metal.

The subject matter of this application includes, in some respects, improvements on the subject matter shown in United States Letters Patent Number 1,143,101, granted June 15, 1915, for improvements in metal drawing machines, granted upon an application filed by me July 24, 1912, Serial

Number 711,208, in which I have claimed certain subject matter herein shown and described but not herein claimed.

In order that my invention may be more readily understood and further objects of the invention more fully appear, I will first describe an apparatus for drawing hot metal tubes embodying the present preferred form of my invention, and I will thereafter particularly point out the features of my invention in the appended claims.

In the accompanying drawings of said apparatus, Figure 1 is a side elevation of a metal-drawing machine or apparatus embodying the preferred form of my invention; Fig. 2 is a top plan view of the same; Fig. 3 is an enlarged elevation of a part of the machine showing the die apparatus proper and other parts in section; Fig. 4 is a further enlarged sectional view of the die mechanism proper; Fig. 5 is a fragmentary sectional view taken on line 5—5 of Fig. 4; Fig. 6 is a fragmentary sectional view taken on line 6—6 of Fig. 4; Fig. 7 is a greatly enlarged longitudinal sectional view of a part of the device shown in Fig. 4; Fig. 8 is a cross-sectional view taken on line 8—8 of Fig. 3; and Fig. 9 shows a die mechanism with a plurality of raceways.

Referring to the drawings, Figs. 1 and 2, 85 1 is a platform or table on one end of which is mounted a rotary motor 2, on the frame of which the ball die mechanism 3 is journaled, as hereinafter referred to. To the left of this mechanism I provide a furnace such as 90 a gas furnace 4, mounted on legs 5 and having a series of gas pipes 6. This furnace is hollow so as to permit the insertion of a mandrel 7 therethrough when tubes are being drawn, and so as to receive the tube 8 to 95 be heated and drawn.

At the rear of the motor a trackway 9 extends along the table in alignment with the die. A draw head 10 and a following block 11 are mounted on the trackway, and the following block is provided with a pair of tongs 12 having their gripping jaws 13 adapted to grip onto a plug or other suitable means 14 secured in the end of the tube 8 to be drawn, while the other extremity of the tongs is provided with toggle links and a connecting hook 15 connecting the tongs to the draw head 10, which is in turn provided with a pivotal hook 16 having a handle 17 by means of which it is lifted into 110

and out of engagement with an endless chain 18 passing over sprocket wheels 19 and 20 mounted near the opposite ends of the table. The chain is driven by means of a suitable motor 21 geared to the sprocket wheel 20 through the gear wheels 22, 23, 24, 25.

When the machine is used for drawing tubes instead of rods, I provide the mandrel 7 above referred to, which is supported at one end in an open slot 26 in the head of a pillow block 27. The mandrel is preferably of considerably less diameter than the tube to be drawn, and extends through the furnace 4 to the ball die mechanism proper and is provided with an enlarged head 28 lying within the ball die mechanism and of the desired inner diameter of the finished tube.

Referring to Figs. 3-5, a hollow spindle 29 is journaled in a ring 30 fitting in an annular recess of a projection 31 formed on the left-hand frame of the motor 2, the ring being provided with ball bearings 32. A rotating supporting frame or die block 33 is threaded and keyed onto the extremity of the spindle and is provided with an opening in which suitable die ball-supporting parts, such as relatively adjustable die cheek plates 34 and 35, are secured, the cheek plate 35 being preferably threaded into the die block 33, the cheek plate 34 being keyed to said die block so as to slide in and out therein. The adjacent surfaces of the two cheek plates form a raceway 37 for the die balls 38, and the balls are retained in this raceway by means of a retaining ring 39 (Figs. 3 and 4). The cheek plates being secured to the die block 33, rotate therewith, but the cheek plate 34 is so keyed to the block that it may slide longitudinally therein for the purpose of varying the diameter of the die, which is accomplished by the inclined surface 40 of the cheek plate 34 forcing the balls inward or permitting them to move outward, according as the cheek plate is moved toward or away from the cheek plate 35. The adjustment of the cheek plate 34 is accomplished in the present form of my invention, by means of an adjusting device 41 having an annular flanged portion 42 threaded onto an annular frame 43 which is keyed to the projection 31 from the motor frame. The adjusting device, which is in the form of a cap, has an end portion 44 surrounding the end of the die block 34 and is provided with an opening 45 in alignment with the hollow spindle 29.

The end portion 44 of the adjusting device is intended to thrust inwardly against the cheek plate 34, and in order to avoid friction between said device and the adjacent cheek plate 34 in adjusting the die while the machine is in operation, and to take up any thrust from the die balls, I provide ball bearings 46 between the cheek plate 34 and the said surrounding portion

44 of the adjusting device; and I also provide ball bearings 47 between the inner end of the die block 33 and the adjacent wall of the annular frame 43 for taking up the thrust of the die balls, which will be exerted through the die block and said bearings against the frame of the motor.

The adjusting device 41 is operated by a handle or pin (not shown), which is adapted to fit into holes 49 around the circumference of the flange 42 of the adjusting device by means of which the adjusting device may be screwed in and out along the annular threaded extension 43' of the frame 43.

If it is desired to reduce the diameter of the die, the operator inserts the handle 48 in one of the sockets 49 on the adjusting cap 41, and rotates it in a direction to move it toward the motor, whereupon the inward thrust of the cap upon the cheek plate 34 causes the same to be moved inwardly, forcing its tapering surface against the die balls to move them inwardly, to reduce the diameter of the die. Conversely, if it is desired to enlarge the diameter, the operator rotates the adjustable cap 41 in the opposite direction, relieving the plate 34 of the thrust, so that when the tube is pulled over the mandrel against the die balls, it forces the balls outwardly, thereby shifting the die plate 34 outward against the adjusting cap, thereupon permitting the balls to move out radially by reason of the upwardly flaring surface of the said cheek plate 34, resulting in an enlargement of the diameter of the die.

In the present form of my invention, the annular flange 42 of the adjusting device and an adjacent part of the stationary frame 43 are provided one with a graduated scale 50 and the other with a pointer 51 whereby the adjusting device may be set within proper limits for any desired diameter to which the tube or rod is to be drawn down. By this arrangement, each time after the tube has been drawn through the machine the ball die may be adjusted for the succeeding draw without having to shut down the machine.

In order to efficiently draw tubes or rods with a rotary ball die, it is important that the die should rotate at a high speed, and in order to accomplish this purpose and to simplify the machine, the motor 2 is mounted on the table in alignment with the ball die and the rotor 52 of the motor is directly connected to the hollow spindle 29. In the present form of my invention I use an electric motor to drive the hollow spindle, and mount the armature of the motor on an extension 29' of the hollow spindle 29, the two parts of the spindle being provided with flanges 53 secured together by bolts 54, although it will be understood that any suitable drive may be adopted for rotating the rotary die parts.

With the exception of the furnace 4, so much of the apparatus as has already been described is in general somewhat similar to the apparatus forming the subject matter of my above-mentioned co-pending application, and in so far as it is similar it is covered by said application.

I have found in practice that in the operation of ball dies for drawing metal, and particularly in the drawing of metal tubes, the surface of the finished tube is marked or slightly corrugated by the action of the rotating die balls, and in order to overcome this difficulty and render the product smooth, I provide the head 28 of the mandrel with a groove 56 lying substantially in the plane of the raceway, and preferably of a radius larger than the radius of the die balls operating in connection therewith, the forward edge of the groove being preferably slightly higher than the rear edge. The object of providing this groove is to permit the die balls to crowd the metal down into the groove as it is drawn between the balls and the mandrel, and cause it to be stretched as it is drawn out over the rear edge of the groove, this operation overcoming the corrugations or marks that would otherwise appear on the tube due to the action of the die balls thereon. Where hot tubes are to be drawn with the apparatus, I provide the mandrel 7 in the form of a hollow tube having the enlarged head 28 hollow, and through the hollow mandrel I pass a small tube 57 preferably extending from the tail end of the mandrel and through the same to the enlarged head. I connect this tube up with a suitable source of cooling fluid 58, from which water will be discharged into the tube, from whence it will flow to the hollow head and out again through the hollow mandrel 7. This flow of water will prevent the mandrel from becoming overheated by the furnace and the hot tube. In the preferred embodiment of the invention the enlarged head of the mandrel is made of hard steel to prevent wearing.

I have found in the operation of apparatus of this character for drawing hot metal, that it is exceedingly important, if not necessary, to cool the die parts, and in the case of ball die apparatus, to preferably bring the cooling fluid directly in contact with the die balls to more readily cool them. I have also found it extremely important, if not necessary, particularly with ball die apparatus for drawing metal, to remove the scale which accumulates from the tube being drawn. Such scale interferes with the die balls, and in the case of apparatus using die balls in a raceway, it clogs the raceway so as to seriously interfere with, if not prohibit, the proper operation of the apparatus; and one feature of my present invention contemplates the cooling of the die

parts and the removal of the scale. It is important, if not necessary, in doing this, to prevent the cooling fluid from coming in contact with the hot metal being drawn, or otherwise chilling the same, since this would seriously interfere with, if not prevent, the hot drawing of the metal.

In order to attain the above objects without chilling the hot metal, where hot metal is being drawn, I deliver fluid to the rotating die parts in such manner that it is caused by centrifugal force to flow against the die parts and out through passages arranged for its outlet. In the present embodiment of the invention the die cheek plates 35 and 34 which form the raceway between them for the die balls, are so arranged as to provide an annular passage 60 (Figs. 4 and 7) leading therefrom and communicating with a series of openings or passages 61 leading to the inner surface of the rotary spindle 29.

The outer end of the cheek plate 34 is provided with an annular flange 62 projecting inward radially, so that the opening through said cheek plate is of less diameter than the inner diameter of the hollow spindle 29; and I provide means, such as a suitable pipe 63, having a flattened extension 64 projecting through the opening of cheek plate 34 and curved at its extremity so as to discharge the cooling fluid, preferably water, into the raceway, just within the annular flange of said cheek plate. The object of this is to have the water so contained at the end of the die apparatus where delivered, that a slight "head" will be maintained between the delivery and discharge ends. When the fluid is to flow through the spindle it is thus delivered into the rotating parts adjacent a portion of less radius from the center of the "pass" than the inner radius of the spindle, so as to provide this slight "head" to cause the water to flow from said point of delivery, across the raceway and through the passages or openings 60, 61, into the hollow spindle and along the inner surface of the same, to a hood 65 (Figs. 3 and 8). Only a slight "head" is necessary to cause the water to take this course through the spindle, since the action of the centrifugal force is so great that a large amount of water will be caused to flow through the parts with an extremely slight "head" between the delivery point and the inner surface of the spindle. For example, I have found that with the apparatus stationary, only an extremely small stream of water will trickle through the apparatus, while with the apparatus running, a considerable amount of water will be caused to flow through the apparatus, due to the centrifugal force acting upon the water delivered to the rotating parts of said apparatus. The centrifugal force tends to throw the wa-

ter outward radially, so that in order to have it flow through the spindle rather than leak over the annular flange of the cheek plate 34, it is necessary that said flange should be extended inwardly nearer to the axis of the "pass" than is the inner surface of the spindle. While in drawing hot metal it is desirable to convey the cooling fluid off through the spindle in this manner so as not to have it leaking over the apparatus and possibly getting in contact with the hot metal being drawn, yet it will be obvious to those skilled in the art, after understanding my invention, that the water may be otherwise led off through the die apparatus from the raceway.

While I have shown and described a machine in which die balls are used and in which the fluid is brought in direct contact with the balls to more readily cool them and to wash away scale, obviously the cooling fluid may be caused to flow in other channels to cool the die parts. The passages 61 for fluid, above referred to, may be arranged in any suitable way, such as by drilling a series of holes through the cheek plate 35, as shown. In order that the water may not be forced by the relatively great centrifugal force through the different parts of the die apparatus and come in contact with the hot tube, I provide a packing ring 68 between the die block 33 and the cheek plate 34, to prevent the flow of the cooling fluid between these two parts; and I provide a second packing ring 69 to prevent the flow of liquid between the die block and cheek plate 35.

The operation of the machine described is as follows: The mandrel 7 is lifted out 40 of the socket 26 and the tube 8 to be drawn is slipped over the rear end of the mandrel and into the furnace 4 where, after its forward end has been heated, the plug 14 is threaded or otherwise secured into the forward end of the tube and gripped by the tongs 12, which are then connected to the draw head 10. The motor 2 driving the ball die is then started up, the cooling fluid turned on, the adjusting cap 41 moved to 50 the desired setting, as indicated by the scale 50, and the handle 17 of the draw head is then operated to throw the hook 16 into engagement with one of the links of the endless chain 18, whereupon the tube is drawn forward through the ball die, the die balls forcing the tube against the mandrel head to reduce the thickness of the metal, the metal, in the present form of the invention, as previously pointed out, being forced by the die balls into the groove 56 and stretched over the rear edge of the same in leaving the groove, to obviate any ball marks thereon. After the tube has been completely drawn through the die, the handle 17 will be thrown back to release the hook in the well

known manner, whereupon the die is adjusted for the next draw and the operation repeated.

The form of the machine shown in Fig. 9 provides for the use of two separate sets of die balls 75, 76, which may be so arranged and constructed as to reduce the thickness of a tube by two steps during one drawing operation without altering its inner diameter; but in the form of the invention shown, the two sets of die balls are used, the forward set to reduce the thickness of the tube, and the second set to reduce the inner diameter of the tube without reducing its thickness. In this form of the machine the annular supporting frame 77, with the adjusting cap 78 and the thrust ball bearings 79, 80, the spindle 81 and the ball bearings 82, are all substantially as shown and described in the foregoing form. But in order to use the two sets of balls to advantage in the various uses to which the apparatus may be put, it is important to be able to independently adjust the diameter of the die at each set of balls, and to do this it is necessary to independently adjust two of the die cheek plates. To this end, I provide the die block 83 with an intermediate stationary cheek plate 84, which may be rigidly secured to the die block in any suitable manner. On each side of this cheek plate I provide longitudinally shiftable cheek plates 85, 86. The cheek plate 85 has an upwardly tapering surface 87 forming, with the adjacent surface of the cheek plate 84, a raceway for the set of die balls 75, and this raceway is adjustable to vary the diameter of the die at this set of balls, in the manner already described with reference to the first form of the invention. The other cheek plate 86 is suitably threaded onto the end of the spindle 81 by means of a lateral annular flange 88 which is internally threaded and which on its outer surface is provided with gear teeth 89 meshing with a pinion 90 set on a stub shaft 91 mounted in the die block 83. This pinion in turn meshes with an internal gear 92 cut on an annular flange projecting from an adjusting ring 93 loosely mounted on the die block so as to be shifted thereon. This ring is provided with a series of holes 94 lying in the same plane with a second series of holes 95 drilled in the die block. The outer stationary annular frame 77 is provided with a slot 96 also in the plane of said holes, so that if it is desired to shift the cheek plate 86 to the left so as to force the die balls 76 down the inclined surface 97 of cheek plate 84 to reduce the diameter of the die at this set of balls, it is only necessary to insert a pin through slot 96 into one of the holes 94 and rotate the ring 93 in a direction which will cause cheek plate 86 to rotate through the intermediation of gear teeth 92, pinion 90 and gear teeth 89, in a

direction to screw it along the threads 98 toward cheek plate 84. To increase the diameter of the die, the ring 93 is operated in the opposite direction. When the machine is operating the cheek plate 86 is held from longitudinal movement by extending a pin through one of the holes 94 of ring 93 into one of the holes 95 of the die block 83, so as to lock said cheek plate and die block 10 from relative rotation by means of the connection through the aforementioned gearing.

Where the device is used as herein shown, to reduce the thickness of the metal by the action of the first set of die balls, and to reduce the inner diameter of the tube by the action of the second set of die balls without reducing its thickness at that point, I provide a mandrel preferably having an enlarged head 99 and preferably having a groove 100, as and for the purpose heretofore described in connection with the first form of the machine, and also having a section 101 of reduced diameter forming a shoulder 102 just beneath the forward edge of the second set of balls, over which shoulder these balls force the metal to reduce the inner diameter of the tube, simultaneously with the reduction of the thickness of the 30 tube by the advance set of balls.

If desired, the mandrel may be cooled by fluid passed therein by means of a pipe 103 as described in connection with the first form of the invention. The two sets of die 35 balls as herein used may be cooled, and the scale washed from the raceway in the same general manner as heretofore described, it being only necessary to provide passages 104 extending through the intermediate cheek plate 84 to connect the raceways 105 and 106, and to provide passages 107 from the last raceway to the inner surface of the hollow spindle. Water or other cooling fluid is delivered, as heretofore described, within the radially projecting lip 45 or flange 108 of the cheek plate 85.

The operation of this form of the machine is in general similar to the operation of that heretofore described, except that the diameter of the dies at the second set of balls is adjusted by calculation or trial before the actual drawing of the commercial metal, whereas, the forward set of balls may be adjusted while the machine is running.

55 While I have described in detail an apparatus embodying the present preferred form of my invention, it will be obvious to those skilled in the art, after understanding this invention, that various modifications and 60 changes may be made therein within the scope of the appended claims.

Having thus described my invention, what I claim as new and desire to secure by Letters Patent, is:—

65 1. In apparatus for drawing hot metal,

the combination of a rotary frame, a metal-drawing die carried by said frame, means for rotating said frame, means for delivering a cooling fluid to said die, and one or more passageways leading from the die 70 through which the cooling fluid is forced by centrifugal force due to the rotation, whereby the fluid is prevented from reaching the hot metal being operated upon by the die.

2. In apparatus for drawing hot metal, the combination of a rotary frame and a concentrically alined hollow tube connected to rotate therewith, means for rotating said frame and tube, a metal-drawing die 80 mounted in said frame, one or more passageways leading from the die to the hollow tube to convey fluid from the die to the tube, and means for delivering fluid to the die at a point from whence it is forced by centrifugal force through the one or more passageways into the hollow tube and caused to flow along the inner surface of the same.

3. In apparatus for drawing hot metal, the combination of a plurality of annular 90 supporting plates, rotary die bodies supported thereby, means for rotating said plates, and means for delivering a cooling fluid to said rotary plates at a point from whence it will be forced by centrifugal force 95 to flow through said apparatus in engagement with the supporting plates and be prevented from coming in contact with the hot metal being drawn.

4. In apparatus for drawing metal, the 100 combination of rotary means including supporting plates for rotary die bodies, the adjacent surfaces of said plates forming an annular groove between them having one or more fluid outlets therefrom, means for rotating said first means, rotary die bodies located in said groove, means for delivering fluid to said groove where it is prevented by centrifugal force from reaching the hot metal being drawn and is forced 105 through the one or more outlets.

5. In apparatus for drawing metal tubes, the combination of die ball-supporting means having an annular raceway, die balls in said raceway, one or more fluid outlet 115 passages from said raceway, means for delivering fluid to the inner surface of the ball-supporting means at a point of less radial distance from the axis of the "pass" than the radial distance of the bottom of 120 the groove, from which point of delivery the fluid will be caused by centrifugal force to flow into the bottom of the groove and through said outlet passages.

6. In apparatus for drawing metal, the 125 combination of a rotary member with a rotary spindle attached thereto, die ball-supporting parts carried on said member, said ball-supporting parts forming a raceway therebetween having one or more outlet pas- 130

sages leading to the spindle, die balls in said raceway, and means for delivering liquid within said rotary member at a point from whence it will be caused by centrifugal force to flow to the bottom of the raceway and through the outlet passage or passages to wash out the scale from the metal.

7. In apparatus for drawing metal, the combination of rotary means for supporting die balls, said means having an annular raceway, one or more outlet openings for fluid from the raceway, die balls in said raceway, means for rotating said supporting means, and means delivering liquid to the raceway at a point of less radial distance from the axis of the "pass" than the radial distance from the bottom of the raceway, from whence the liquid will be caused by centrifugal force to be distributed within the raceway and flow from thence through the passage or passages to wash out the scale from the metal.

8. In apparatus for drawing metal, the combination of a hollow rotary spindle, die ball-supporting means carried on said spindle and provided with a raceway having one or more fluid outlet passages therefrom leading to the inner surface of the hollow spindle, die balls in said raceway, and means for delivering liquid to the raceway at a point the radial distance of which from the axis of the "pass" is less than the inner radius of the hollow spindle, whereby the liquid will be caused by centrifugal force to flow from its point of delivery into the raceway and through the said fluid outlet passage or passages to the inner surface of the spindle and along the same.

9. In apparatus for drawing metal, the combination of rotary means including die ball-supporting plates and a hollow tube connected to rotate therewith, means for rotating said first means, the adjacent surfaces of said plates forming between them an annular raceway, one or more passages connecting the raceway and tube for conducting fluid from the raceway to the inner surface of the tube, die balls in said raceway, and means for delivering fluid to the raceway at a point from whence it is caused by centrifugal force to flow around and partly fill the raceway and flow therefrom through the one or more passages longitudinally of the apparatus and into the tube and along the inner surface of the same.

10. In apparatus for drawing hot metal tubes, the combination of a hollow rotatable spindle, a die block carried at one end of the spindle and having an opening therein in alignment with the spindle, die cheek plates mounted in said opening and relatively adjustable axially of the spindle and having an opening therethrough concentric with the spindle, a raceway for die balls formed in the adjacent surfaces of the plates

and having an inclined wall, a series of die balls in said raceway, one or more passages leading from said raceway to the inner surface of said spindle for conveying fluid from the raceway to said spindle, means for delivering fluid to the inner surface of the cheek plate farthest away from the spindle, at a point the radial distance of which from the axis of the "pass" is less than the inner radius of the spindle, from which delivery point the fluid will be caused by centrifugal force to flow across the raceway and from thence through the passages and along the inner surface of the spindle to prevent the chilling of the hot metal tube by the fluid.

11. In apparatus for drawing hot metal tubes, the combination of a hollow rotary die block, die cheek plates mounted in said die block and relatively adjustable axially thereof and having an opening therethrough, a raceway for die balls formed in the adjacent surfaces of the plates and having an inclined wall, a series of die balls in said raceway, one or more passages leading from said raceway for conveying fluid therefrom, means for delivering fluid to the inner surface of one of said cheek plates, at a point the radial distance of which from the axis of the "pass" is less than the radial distance to the bottom of the raceway, whereby fluid will be caused by centrifugal force to flow into and out of the raceway, a mandrel extending within the die and having a groove formed therein lying substantially in the plane of the raceway, said groove being of larger radius than the radius of the die balls, whereby the metal of the tube will be crowded into the groove by the rotating balls and again stretched as it leaves the exit side of the groove to prevent markings in the finished product due to the action of the die balls.

12. In apparatus for drawing hot metal tubes, the combination of die ball-supporting means having an annular raceway, die balls in said raceway, means at the intake end of the die for heating the tube, a mandrel extending into the die and against which the tube is forced by the die balls to draw it, one or more fluid outlet passages from said raceway, means for delivering fluid to the inner surface of the ball-supporting means at a point of less radial distance from the axis of the "pass" than the radial distance of the bottom of the raceway, from which point of delivery the fluid will be caused by centrifugal force to flow into the bottom of the raceway and through said outlet passages to cool the die balls.

13. In apparatus for drawing hot metal tubes, the combination of die ball-supporting means having an annular raceway, die balls in said raceway, means at the intake end of the die for heating the tube, a hollow mandrel extending through the heating means

- and into the die and against which the tube is forced by the die balls to draw it, and means for conveying a cooling fluid into the mandrel to cool the same.
- 5 14. In apparatus for drawing hot metal tubes, the combination of die ball-supporting means having an annular raceway, die balls in said raceway, means at the intake end of the die for heating the tube, a mandrel extending into the die, said mandrel being provided with a groove lying substantially in the plane of the raceway and into which the metal is forced by the die balls in the drawing operation to prevent the 10 balls from marking the finished tube, one or more fluid outlet passages leading from the die ball raceway, means for delivering fluid to the inner surface of the ball-supporting means at a point of less radial distance from 15 the axis of the "pass" than the radial distance of the bottom of the groove, from which point of delivery the fluid will be caused by centrifugal force to flow into the bottom of the groove and through said outlet 20 passages.
15. In apparatus for drawing metal tubes, the combination of rotatable supporting parts for die balls, said supporting parts being provided with a plurality of annular 25 raceways, a set of die balls in each raceway, and a mandrel extending within the die and against which the first set of balls forces the tube to reduce its thickness, said mandrel having a shoulder of reduced section substantially adjacent the second set of balls against which the balls force the tube to 30 reduce its inner diameter.
16. In apparatus for drawing metal tubes, the combination of rotatable supporting 35 parts for die balls, said supporting parts being provided with a plurality of annular raceways, a set of die balls in each raceway, a mandrel extending within the die and against which the first set of balls forces the tube to reduce its thickness, said mandrel having a shoulder of reduced section substantially adjacent the second set of balls against which the balls force the tube to 40 reduce its inner diameter, one or more passages for conveying fluid from one raceway to the other and out therefrom, and means for delivering fluid to one of said raceways at a point from whence it will be caused by centrifugal force to flow through said raceways and passages.
- 45 17. In apparatus for drawing metal, the combination of a rotary die block, means for rotating the same, a plurality of die cheek plates carried on said block and relatively 50 adjustable axially of the "pass," said plates forming between them two raceways for 55 separate sets of die balls, die balls in said raceways, and means for individually adjusting two of said cheek plates axially to separately vary the diameter of the die at 65 the two raceways.
18. In apparatus for drawing metal, the combination of a rotary die block, means for rotating the same, a plurality of die cheek plates carried on said block and relatively 70 adjustable axially of the "pass," said plates forming between them two raceways for 75 separate sets of die balls, die balls in said raceways, means for individually adjusting two of said cheek plates axially to separately vary the diameter of the die at the two raceways, one or more passages for conveying fluid from one raceway to the other and out therefrom, and means for delivering fluid to one of said raceways, at a point from 80 whence it will be caused by centrifugal force to flow through said raceways and passages.
19. In apparatus for drawing metal tubes, the combination of a rotary die block, means for rotating the same, a plurality of die 85 cheek plates carried on said block and relatively adjustable axially of the "pass," said plates forming between them two raceways for 90 separate sets of die balls, die balls in said raceways, means for individually adjusting two of said cheek plates axially to 95 separately vary the diameter of the die at the two raceways, and a mandrel extending into said die and against which the tube is forced during the drawing operation.
20. In apparatus for drawing metal tubes, the combination of a rotary die block, means for rotating the same, a plurality of die cheek plates carried on said block and relatively 100 adjustable axially of the "pass," said plates forming between them two raceways for 105 separate sets of die balls, die balls in said raceways, means for individually adjusting two of said cheek plates axially to 110 separately vary the diameter of the die at the two raceways, and a mandrel extending into the die, said mandrel having a portion against which the metal of the tube is pressed by one set of die balls to reduce the thickness of the metal during the drawing operation, and having a portion of reduced diameter 115 providing a shoulder adjacent the other set of die balls against which shoulder said last set of die balls acts to force the tube to reduce its inner diameter.

In testimony whereof, I have signed my name to this specification, in the presence of two subscribing witnesses.

LOUIS H. BRINKMAN.
